[57] CLAIM

The ornamental design for male tape for surface fastener, as shown and described.

DESCRIPTION

FIG. 1 is a top plan view of a male tape for surface fastener showing my new design;
FIG. 2 is a front elevational view thereof;
FIG. 3 is a bottom elevational view thereof;
FIG. 4 is a right side elevational view thereof;
FIG. 5 is a left side elevational view thereof;
FIG. 6 is a rear elevational view thereof;
FIG. 7 is a perspective view thereof;
FIG. 8 is a cross-sectional view taken along lines 8—8 of FIG. 1; and,
FIG. 9 is a view similar to FIG. 8 showing the way the male tape for surface fastener of FIG. 1 is used.
The broken line showing of the surface fastener in FIG. 9 is for illustrative purposes only and forms no part of the claimed design.
